PRINTING DEVICE

William L. McCarter, Portland, Oreg., assignor of
one-half to C. H. Farrington, Portland, Oreg.

Application May 6, 1939, Serial No. 272,197

12 Claims. (Cl. 101—214)

My invention relates to printing presses for printing on paper, or the like, and it relates more particularly to an attachment for existing presses for printing supplementary matter in color. There are in use a large number of printing presses that give good service in printing in black, or in any one color, but which are not adapted to print more than one color on the same sheet. In many cases, such for example as in printing newspapers, the value of these presses would be considerably increased by an attachment that would render them suitable for multi-color printing.

The provision of such an attachment has, however, met with considerable difficulty in that, for one reason, it has not been found possible heretofore to print supplemental matter on paper without disturbing its path through the existing press, and said disturbance has necessitated careful reorganization of the entire machine, a procedure unjustifiably expensive. I propose to provide an attachment for a printing press adapted to print on paper at some point on its normal path through said press, without disturbing the normal travel of said paper along said path.

A further reason for the aforesaid difficulty arises from the fact that the available locations for an attachment for an existing printing press are subject to considerable vibration, resulting in an irregular application of force between the type and whatever backing material is used on the other side of the paper. It is impractical to eliminate said vibration by heavy construction of the attachment inasmuch as the press itself is not ordinarily sufficiently sturdy in those parts on which an attachment might be mounted; it is usually necessary to mount said attachment on the uppermost portion of the press.

In their most common form, printing presses have embodied metal type positioned either upon the surface of a cylindrical roller or upon a flat bed. The paper to be printed has been squeezed between said type and a backing member carrying the impression of said type in intaglio, the backing member registering precisely with said type at all times. The amount of vibration to which an attachment is subjected would be intolerable with metal type. The paper would be torn by vibration in a plane parallel to itself, and it would be "punched" by vibration in a plane normal to itself, that is, the type would tend to pierce the paper. Furthermore, said vibration would result in damage to said metal type and its intaglio image in the backing material and the printing would blur on the paper.

My invention is particularly adapted to be used on flatbed web type presses. In a press of this character, the paper moves as a continuous web through the machine and is intermittently fed to the printing or impressing mechanism.

It moves at a more or less uniform speed through the forming, folding and cutting mechanism and tension producing devices must thus be provided between the impression mechanism and the folding mechanism for taking up the slack produced by the intermittent feed through the impression mechanism. As the web moves to the forming mechanism, it passes over a series of guide rollers. One of said guide rollers has a peripheral speed greater than the web's speed, and said roller thus slips on the web and is designed to maintain a predetermined degree of tension in the web.

There is no convenient location adjacent the impression mechanism for providing an imprinting device. The web also moves at a varying speed so as not to be adapted to be printed conveniently by a printing device. The slack take-up mechanism also provides no convenient location, and as the web moves to the forming mechanism, it is threaded about a series of rollers which are of relatively small diameter, vibrate substantially and which if driven at all are not driven synchronously with the speed of the web.

I have discovered that I can provide an imprinting device adjacent the forming portions of a web type press by providing a printing roller carrying rubber type faces or type faces having a certain factor of resiliency so that any vibration present can be absorbed by the type faces. Also, the resiliency of said type faces permits them to correspond to the arcuate surface of the rollers in this portion of the machine. This is not possible with metal type and any other type of printing device with which I am familiar produces frequent web breakage because of the effect of said imprinting device upon the paper for the reasons heretofore enumerated. Poor printing also results and inaccuracy of registration is so prevalent that said imprinting devices were deemed impractical. With an imprinting device having said resilient type faces, the latter are adapted not only to co-operate with rollers moving either faster or slower than the web, but said imprinting device with said type of type faces is adapted to co-operate with and conform to a flat immovable guiding surface. Said printing faces are adapted to be arranged in operating relation to a backing surface which is relatively smooth and hard rather than yielding to accommodate said type because this type has sufficient resiliency in itself to accommodate the constantly differing operating pressures which are produced by the conditions which exist at this point. If said type faces are made of rubber, they require such very light pressure for good printing that good printing is obtainable even under these adverse conditions.

The principal object of my invention is to provide an imprinting attachment for an existing

printing press and particularly one for color printing that can be easily attached to said press without changing the path of the paper there-through. I attain said object by providing a 5 printing roller having rubber type faces adapted to bear against said paper so lightly that the backing roller therefor need not travel at the same speed as the paper, and that will yield under vibration and operate successfully despite 10 the vibration to which said attachment will necessarily be subjected.

A further object of my invention is to provide a printing roller whose position with respect to a backing roller is adjustable, said backing roller 15 remaining stationary.

A further object of my invention is to provide means for automatically compensating the angular position of a printing roller of a printing attachment for the irregular longitudinal motion of 20 the paper when said attachment is used with a flat-bed web press in which the printing operation proceeds alternately in opposite directions along the paper. Said compensation is necessary to prevent faulty registration of the matter 25 printed by the attachment with that previously printed.

A further object of my invention is to provide a plurality of rollers adapted to be moved laterally to carry ink from an ink roller to another stationary roller from which said ink is carried to the printing roller, said movable rollers being in contact with each other to carry ink progressively from one to another. Laterally movable single rollers have heretofore been used to carry ink, 35 but a single roller does not spread ink uniformly over its surface while moving, whereas a plurality of rollers transferring ink from one to the other and squeezing it therebetween effectively spread said ink. Uniform distribution of ink on the 40 printing rolls is an important matter in all printing operations, and it has heretofore been known that said distribution might be effected by a series of rollers. I have found that space can be saved, and better distribution of ink achieved with an 45 attachment having a series of laterally movable rollers; and I prefer that said rollers be of different diameters.

A further object of my invention is to provide a yieldable support for a laterally movable roller 50 adapted to carry ink from an ink roller to a printing roller, or to other rollers leading thereto, whereby the travel of said movable roller will be automatically caused to conform to the distance between said rollers. The significance of said 55 yieldable feature will be readily apparent when it is considered that I propose to move the aforesaid printing roller laterally to vary the distance between it and the backing roller, but I do not wish to move the ink roller, and its accompanying 60 mechanism. It follows that the distance between the ink roller and the printing roller will be subject to change, and it is desirable that the aforesaid travel of the ink-carrying roller shall conform to such change without manual adjustment.

A further object of my invention is to provide 65 control means whereby a printing attachment may be caused to print precisely in a predetermined position relative to matter previously printed on the same paper. I attain said object by so arranging the printing roller of said attachment that it may readily be moved longitudinally of itself, which is laterally with reference to the paper being printed, until the type thereon is 70 properly located laterally on said paper. I also

provide means whereby said printing roller may be rotated independently of said paper for the purpose of moving said type to the proper location longitudinally thereof. I deem it preferable, in a printing attachment, to move the printing 5 roller rather than the paper in bringing the two into their proper juxtaposition.

This application is a continuation in part of my co-pending application entitled Color-printing attachment for printing presses filed in the United 10 States Patent Office May 11, 1938, Serial No. 207,248.

Other objects and advantages will be disclosed with reference to the accompanying drawings, in 15 which:

Fig. 1 is a side elevation of a printing press and an attachment therefor embodying my invention;

Fig. 2 is a fragmentary perspective view of the upper portion of the printing press shown in Fig. 1, the paper therein being arranged to follow a 20 different path, and the printing attachment being shown by dotted lines in a different position, along the side of said press;

Fig. 3 is a fragmentary view of a portion of a 25 printing press in which the attachment of Fig. 1 is arranged to print against a stationary metal surface instead of against a roller;

Fig. 4 is a foreshortened plan view of the attachment of Fig. 1, together with fragments of 30 the printing press shown therein;

Fig. 5 is a section taken along the line 5—5 in Fig. 4;

Fig. 6 is side elevation of the structure shown in Fig. 4;

Fig. 7 is a diagrammatical sectional view of the 35 rollers of Fig. 4;

Fig. 8 is an enlarged fragmentary detail view of a support for the movable ink carrying rollers of Fig. 4, a portion thereof being shown broken away to show the arrangement of the adjusting 40 screws;

Fig. 9 is a sectional detail view taken on the line 9—9 in Fig. 4 with parts shown broken away to illustrate details of construction;

Fig. 10 is a section taken along the line 10—10 45 in Fig. 4, the ink carrying rollers being shown in their rearward position;

Fig. 11 is an enlarged front elevation of the compensator shown in Fig. 4;

Fig. 12 is a back view of the compensator shown 50 in Fig. 11;

Fig. 13 is a plan view of said compensator, a portion thereof being shown broken away to disclose the internal structure;

Fig. 14 is an enlarged, foreshortened plan view 55 of the printing roller shown in Fig. 4, a portion thereof being shown broken away to disclose the blanket tightening shaft therein;

Fig. 15 is an end view of said printing roller;

Fig. 16 is an enlarged fragmentary sectional view taken substantially along the line 16—16 in Fig. 14, showing the manner in which the blanket is attached to said printing roller;

Fig. 17 is a plan view of said blanket superposed 65 on a copy sheet on which there is printed matter, a patch of rubber type being shown attached to said blanket, and another patch being shown partially attached thereto;

Fig. 18 is a fragmentary sectional view taken 70 along the line 18—18 in Fig. 17, the sections of rubber type, adhesive material, and transparent blanket being shown separated;

Fig. 19 is a diagrammatic view of a printing 75 roller and a backing roller, the position assumed

by said printing roller during vibration being shown on an exaggerated scale by dot-and-dash lines; and

Fig. 20 is an enlarged, fragmentary perspective view of said printing roller and said backing roller showing on an exaggerated scale the manner in which the rubber type on said printing roller yields during vibration.

One type of printing press 1, to which my invention is adapted to be attached, comprises a main frame 2 on which a roll of paper 3 may be rotatably supported on trunnions 4. Said paper is unrolled from said roll in the form of a web, shown in Fig. 1 by dot-and-dash lines. Said web extends rearwardly from said roll over reciprocating roller 5, around impression roller 6 back under impression roller 7 around reciprocating roller 8 and thence to the forming and folding and cutting mechanism hereinafter more fully described. Impression rollers 6 and 7 are carried by crosshead 9 adapted to be reciprocated by side rod 10 driven by crank pin 11 carried by gear wheel 12 driven by pinion 13 fixedly secured to shaft 14 which carries pulley wheel 15 adapted to be rotated by belt 16. Said belt 16 may be driven by any suitable source of power, not shown.

As is well known in the printing art, the aforesaid press is a two-way flat-bed press and is adapted to print on both sides of a web of paper. Impression roller 6 printing on one side and impression roller 7 on the other. Furthermore, and more pertinent to my invention, each of said impression rollers is adapted to print during movement in both directions of crosshead 9. Because the printing operation in a two-way press tends to vary slightly the speed of the web in accordance with the direction the impression roller moves, printing during movement of the impression roller in opposite directions gives rise to an irregular movement of the web commonly known as "hop." The magnitude of this variation in speed will vary considerably, but, in general, it may give rise to a displacement of the web of from one-quarter inch to one-half inch, compared to a uniformly moving web. My invention is not limited to a two-way press but is adapted to any flat-bed web press.

It is well known that reciprocating rollers 5 and 8 are given a substantially vertical motion, as shown in Fig. 1, in synchronism with the motion of crosshead 9 for the purpose of moving the web the proper amount, between strokes of said crosshead, to bring it in the correct position for printing. However, said reciprocating rollers do not prevent the aforesaid "hopping" of the web. It is apparent that said hopping will tend to vary the position of matter printed by an attachment with respect to that printed previously by the printing press, that is, hopping will spoil the register of the matter printed by the attachment unless it is compensated. I hereinafter describe means for said compensation, and said means forms an important part of my invention.

In the mode of application of my invention that I prefer, the printing roller thereof is arranged against one of the forming rollers of an ordinary printing press, such as roller 17, shown in Fig. 1. Said roller is carried by the upper portion of the frame and a substantial distance above the base of the latter. Said roller is driven by sprockets and chains and appropriate gearing from shaft 18 which carries gear wheel 12. It will be understood that, in different

presses, the manner of driving said forming roller will vary somewhat, but insofar as the mode of application of my invention now being considered is concerned, said drive mechanism is unimportant.

It is common practice to drive the forming roller 17, at a peripheral speed somewhat greater than that of the web to take up the slack in the web and keep it taut. The operation of the printing press does not permit of any change 10 in the speed of said roller. It is intended that the web shall slip slightly thereon.

Alternatively, an attachment embodying my invention may be located against any other available smooth roller in the former of said press, 15 such, for example, as roller 19 which is not driven except by the web, or it may be located against any flat, smooth stationary surface at said point over which said web passes such as that shown in Fig. 3. In any case, I prefer to drive my 20 printing roller accurately at the same peripheral speed as the web speed.

Referring now more particularly to the structure embodying my invention, a printing roller 29 adjustably mounted on shaft 21 carried by 25 bearings 22 is adapted to carry rubber type, hereinafter more fully described. Collars 23 threaded on said shaft 21 at either end of said roller are adapted to move the latter endwise, thereby to position said type correctly laterally 30 of the web. Nuts 24 threaded on rods 25 may be turned to move said printing roller toward or from forming roller 17, which now serves as a backing or impression roller, that is, the web is pressed lightly against said backing roller by 35 said rubber type.

The position of said printing roller is adjustable vertically by sliding clamps 26 up or down on posts 27, thereby providing a further adjustment with respect to said backing roller. Said 40 clamps may be secured by caps screws 28, and rods 25 may be threaded firmly in said clamps. It will be understood that, whereas rods 25 and clamps 26 are part of the attachment embodying my invention, posts 27 and brackets 29 supporting backing roller 17 and roller 19 are part of the original printing press.

In any printing operation, it is necessary that ink be supplied to the type uniformly, and it is also necessary that said ink be supplied at a 50 rate that can be varied to suit different conditions. To this end, it has heretofore been found that one of the rollers carrying said ink should move alternately back and forth longitudinally to spread said ink uniformly, and I 55 provide an oscillating roller 30 adapted to be moved endwise by fork 31 pivotally mounted on pin 32 and carrying a roller 33 adapted to engage the side face of cam 34, said face being arranged obliquely with respect to its axis of 60 rotation. Spring 35 is provided to retract said fork after it has been thrust outward by said cam face.

In order to carry ink from said oscillating roller to said printing roller I provide two rollers 36, 65 both adapted to make contact throughout the length of both printing roller 29 and oscillating roller 30. Said rollers 36 may, if desired, be made of rubber. However, it is undesirable that rubber rollers be allowed to stand for even a 70 few hours in contact with other rollers, since flat surfaces would be thereby produced on said rubber rollers. I, therefore, mount oscillating roller 30 on brackets 37 pivotally mounted on pins 38. When the machine is shut down, an 75

attendant may remove the uppermost one of rollers 36 and lift roller 30 upward and backward, out of contact with the lowermost one of rollers 36. I prefer to support said rollers 36 in open bearings, from which they may readily be removed. I drive oscillating roller 30 by a pinion 39 fixedly secured to shaft 40 as is said roller 30. Pinion 39 meshes with pinion 41 which is adapted to mesh with gear 42 when said brackets 37 are lowered. Said gear 42 is affixed to shaft 21 and adapted to be driven thereby.

An ink fountain 43 is adapted to supply ink to ink roller 44 in the usual way. Said ink roller is supported by shaft 45 which carries ratchet wheel 46 adapted to be driven by dog 47 carried by lever 48 which also carries at its opposite end roller 49 adapted to follow the irregular periphery of cam 34. Said lever 48 is fixedly secured to shaft 50 which carries lugs 51, one near either end, adapted to engage springs 52 carried by brackets 53. Said brackets are journalled loosely on said shaft, and are free to be rotated thereon by lugs 51 acting through springs 52. Said brackets 53 are adapted to carry three rollers, 54, 55, and 56, 25 and to move said rollers laterally in response to the action of cam 34.

As cam 34 causes brackets 53 to move back and forth, rollers 54 and 56 alternately come in contact with ink roller 44 and oscillating roller 30, respectively, at the end of the stroke, thereby carrying ink from said ink roller to said oscillating roller from whence it goes to the printing roller. I prefer to make said rollers 54 and 56 of a rubber compound and to make them, and roller 55, of different diameters in order that irregularities on the surface of one roller will not repeatedly meet the same portion of adjacent rollers.

I desire that said rollers 54, 55, and 56 shall rotate to spread the ink thereon, but I do not wish to provide special means for rotating them, such as gears or pulley wheels, because of the difficulty in providing said special means for movable rollers. I, therefore, provide the aforesaid springs 52, one of which permits roller 56 to remain in contact with roller 30, which is driven, for a substantial time at the end of each stroke. Said roller 56 thereby acquires rotary motion from said roller 30, and transmits the same to rollers 55 and 54. The other of said springs 52 permits roller 54 to yieldably contact ink roller 44. When brackets 53 are swung forward by spring 58, acting on lever 58a which is fixedly secured to shaft 50, roller 54 is adapted to be lifted slightly by said ink roller, as is shown in Fig. 6. Then, when cam 34 forces said brackets back against the tension of said spring 58, ink roller 44 is rotated slightly by dog 47, thus bringing a freshly inked portion of said ink roller into position to contact roller 54 on the next stroke.

As mentioned, the "hop" of the web produced by printing operations carried on alternately in opposite directions in a two-way press tends to cause the imprinted matter to register differently with alternate impressions of the original printing. To prevent said faulty registration I provide a register compensator, shown more clearly in Figs. 11 to 13, adapted alternately to increase and decrease the speed of the printing roller between impressions, thereby moving said roller back or ahead slightly with respect to the web.

Roller 17 (see Fig. 1) is part of the original printing press, and it is driven at a definite speed

with respect to the web. I affix pinion 59 to shaft 60 on which said roller 17 is mounted. Said pinion 59 is adapted to mesh with ring gear 61 which is rotatably carried by hub 62 journalled on inner hub 63 which is keyed on shaft 21. Said gear 61, however, is free to rotate on said inner hub only part of a revolution, being restrained by spring 64 engaging bolt 65, or by nuts 66 threaded on said bolt. Said bolt passes through boss 67 on clamping ring 68 secured to hub 62 by bolts 69. The purpose of said clamping ring will be hereinafter described.

Between spring 64 and nuts 66 on bolt 65, lever 70 constructed integrally with inner hub 63 is positioned, said lever rotating with shaft 21. Cam 71 secured to rod 72 journalled in hub 62 is adapted to engage roller 73 carried by lever 70 at the end thereof opposite bolt 65. When said cam is rotated, it will cause shaft 21 to move forward and backward, alternately, with respect to gear 61, or, in other words, it will cause printing roller 20 to move slightly forward or backward with respect to the web. I wish to so move said printing roller at the proper time and the proper amount to compensate for the "hop" of the web. I, therefore, provide a star wheel 74 on the end of rod 72 opposite roller 73, and I position a pin 75 (see Figs. 4 and 6) to engage said star wheel as the latter revolves with gear 61 about shaft 21, thereby rotating said star wheel with respect to said gear.

The aforesaid movement of printing roller 20 with respect to the web should take place between impressions, that is when the margin of the printed matter is opposite said roller, at which time the rubber type carried by said printing roller is not in contact with the web. Star wheel 74 has twice as many lobes as has cam 71 in order that printing roller 20 shall be moved in opposite directions alternately, corresponding to the irregular motion of the web. In order that said movement of said printing roller may be adjusted to occur at the margin of the printed matter, I prefer to secure said pin 75 by means of nut 76 in an arcuate slot 77, whereby said pin may be moved along the path traversed by said star wheel when revolving about shaft 21.

I have hereinbefore described means by which printing roller 20, and the type thereon, may be moved laterally of the web properly to locate the imprinted matter with respect to the previously printed matter. It is also necessary properly to locate said imprinted matter longitudinally of the web. To this end, I provide the structure hereinbefore described whereby ring gear 61 is clamped to hub 62 by clamping ring 68 and bolts 69. To rotate said printing roller, without moving said web, it is necessary only to loosen said bolts, whereupon said roller may be rotated freely.

The method and means for attaching rubber type to a printing roller which I prefer to use with my present invention is the subject of a copending application for United States patent for a Method and means for mounting and registering printing elements, Serial No. 296,273 filed September 23, 1939. Suffice it is to say here that, when a copy has been prepared on which it is desired to imprint special matter, say, in red, said copy may be placed face down over a glass panel thru which sufficient light shines to enable a person looking down on it to see the printed matter thru the copy paper. I then place a transparent blanket 86, which may be made of

some such material as Celluloid, over said copy. I then place rubber type, in small patches, such as 84 and 85, as needed, on said blanket, fastening said type to said blanket by means of sheet adhesive material. Then I place said blanket around printing roller 20, fastening it by hooking eyelets 18 on pins 19, fixedly secured to said roller, wrapping said blanket around said roller and hooking eyelets 80 on pins 81. Said pins 81 are affixed to shaft 82, and rotation of said shaft by spring 83 tends to tighten said blanket on said roller.

It will be seen that, by this method and means, I can see the printed matter of the copy sheet while placing the patches of rubber type, and I can, therefore, properly place said patches with respect to said printed matter. Then, when said blanket is in place on the printing roller, it is only necessary to shift the whole with respect to the web, as hereinbefore described, in order to assure perfect register of the imprinted matter with the original printing. Because the printing roller of the present invention must ordinarily be placed near the top of a printing press where it is not easily accessible, the aforesaid method of attaching rubber type to a printing roller is particularly useful inasmuch as the precise work of placing the rubber type on a blanket is done on a table, instead of on the printing roller. It is then a simple matter to attach said blanket to the printing roller, which may be located in a place so inaccessible as to preclude its use with the older methods of attaching type.

In Fig. 18, portions of patch 84 and blanket 86 are shown with a layer of adhesive material between them, said parts being shown separated. In Fig. 19, rollers 17 and 20 are shown diagrammatically, the movement of roller 20 due to vibration being indicated by its position shown in dot-and-dash lines, said movement being exaggerated. In Fig. 20, the compression of the rubber type due to said vibration is shown, also exaggerated. However, the condition of said type shown in Fig. 20 is not normal and it is undesirable, but it is tolerable with rubber type for brief periods when the press is subject to vibration.

I claim:

1. In a flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a member over which the web is directed while traversing said path, the combination therewith of an imprinting device having a printing roller adapted to engage said web, said imprinting device being carried by said frame, and in operative alignment with said forming member and driven in synchronism with said web.

2. In a flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a roller over which the web is directed while traversing said path, the combination therewith of an imprinting device having a printing roller adapted to engage said web, said imprinting device being carried by said

frame, and in operative alignment with said forming roller and driven in synchronism with said web.

3. In a power driven flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a member over which the web is directed while traversing said path, the combination therewith of an imprinting device having a printing roller adapted to engage said web, said imprinting device being carried by said frame, and in operative alignment with said forming member and driven in synchronism with said web.

4. In a power driven flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a power driven roller driven at such a rate that its peripheral speed exceeds the speed at which the web is fed thru the forming mechanism over which the web is directed while traversing said path, the combination therewith of an imprinting device having a printing roller adapted to engage said web, said imprinting device being carried by said frame, and in operative alignment with said forming roller and driven in synchronism with said web by operative connection with said press, rubber type faces secured to said printing roller, said type faces being operatively aligned with said forming roller, and means for rotating said printing roller so that said type faces move at a speed identical with the web speed.

5. In a flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a roller over which the web is directed while traversing said path, the combination therewith of an imprinting device having a printing roller adapted to engage said web, said imprinting device being carried by said frame, and in operative alignment with said forming roller and driven in synchronism with said web, resilient type faces secured to said printing roller, said type faces being operatively aligned with said forming roller, and means for rotating said printing roller so that said type faces move at a speed identical with the web speed.

6. In a flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a roller over which the web is directed while traversing said path, the combination therewith of an imprinting device having a printing roller adapted to engage said web, said imprinting device being carried by said frame, and in operative alignment with said

forming roller and driven in synchronism with said web, rubber type faces secured to said printing roller, and means for rotating said printing roller so that said type faces move at a speed identical with the web speed.

7. In a two-way flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a roller over which the web is directed while traversing said path, the combination therewith of an imprinting device having a printing roller adapted to engage said web, said imprinting device being carried by said frame, and in operative alinement with said forming roller and driven in synchronism with said web, and means for said printing roller to vary the relative position of the latter during predetermined periods of alternate rotations of said printing roller.

8. In a two-way flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a roller over which the web is directed while traversing said path, the combination therewith of an imprinting device having a printing roller adapted to engage said web, said imprinting device being carried by said frame, and in operative alinement with said forming roller and driven in synchronism with said web, and a register compensating device for said printing roller to vary the relative position of the latter during predetermined periods of alternate rotations of said printing roller.

9. In a two-way flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a roller over which the web is directed while traversing said path, the combination therewith of an imprinting device having a printing roller adapted to engage said web, said imprinting device being carried by said frame, and in operative alinement with said forming roller and driven in synchronism with said web, and a register compensating device for said printing roller to vary the relative position of the latter during predetermined periods of alternate rotations of said printing roller, said register compensating device comprising a cam rotatably carried by the printing roller, and offset from the axis of rotation of the latter, a lever secured to said roller, a relatively fixed stop extending into the path of the cam when it is revolved about the axis of rotation of the printing roller thereby to engage said cam and rotate it to a different position, said cam operatively engaging said lever whereby when said cam is engaged by said stop and moved to a different position, said lever and thereby said printing roller will be rotated slightly with re-

spect to said cam, and with the web of paper upon which said printing roller operates.

10. In a printing press having a main frame and a former disposed at the discharge end thereof, the combination of a supplemental frame disposed above the former, a printing roller rotatably carried by the supplemental frame, an impression roller disposed between the printing roller and the end of the former, gear driven guide rollers arranged adjacent the impression roller and the former, an idling guide roller associated with the gear driven guide rollers and adapted to be rotated by contact with the web, an ink reservoir disposed within the frame, an ink supply roller rotatably mounted in the reservoir, rollers rotatably interposed between the printing roller and the ink supply roller, one of said transfer rollers being rockably mounted with respect to another of said rollers and adapted to periodically convey ink from the ink supply roller to the said one of said ink transfer rollers, another of said rollers being rotatably and slidably mounted within the frame and with respect to said transfer rollers for distributing ink uniformly thereover.

11. In a printing press having a main frame, a printing roller, an impression roller and guide rollers associated therewith for directing a web through the press, and a former arranged at the discharge end of the press, the combination of a supplemental frame disposed above the former, a supplemental printing roller rotatably carried by the supplemental frame, a supplemental impression roller disposed between the supplemental printing roller and the end of the former, gear-driven guide rollers arranged adjacent the supplemental impression roller and the former, an idling guide roller associated with the gear driven guide rollers, and means for applying ink to the supplemental printing roller, whereby a web printed by the main printing roller may receive additional printing upon emerging from the press and passing between said supplemental printing roller and supplemental impression roller.

12. In a power driven two-way flat-bed web press comprising a frame, impression and forming mechanisms, feeding and guiding devices adapted to direct a web of paper successively along a path leading past said mechanisms, the forming mechanism being arranged upon that portion of the frame extending substantially above the base thereof, said forming mechanism including a power driven roller driven at such a rate that its peripheral speed exceeds the speed at which the web is fed through the forming mechanism and over which the web is directed while traversing said path, the combination therewith of an imprinting device having a printing roller adapted to engage said web, said imprinting device being carried by said frame, and in operative alinement with said forming roller and driven in synchronism with said web by operative connection with said press, rubber type faces secured to said printing roller, said type faces being operatively alined with said forming roller, means for rotating said printing roller so that said type faces move at a speed identical with the web speed, and a register compensating device for said printing roller to vary the relative position of the latter during predetermined periods of alternate rotations of said printing roller.

WILLIAM L. McCARTER.
